UNITED STATES PATENT OFFICE.

THOMAS F. HAGARTY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR FOR AUTOMATIC LOOMS.

Application filed January 31, 1927. Serial No. 164,770.

This invention relates to improvement in weft detectors for automatic weft replenishing looms, and particularly in detectors of the "side-slip" type. Such a detector is shown in the prior application of Oscar V. Payne, Serial No. 148,402, in which a weft detector mounted on and movable with the transerrer is disclosed.

My invention relates particularly to the provision of an improved weft-contacting portion or feeler tip, which is to some extent capable of general application, but which possesses special utility when used in the type of weft detector shown in the

15 Payne application.

It is the general object of my invention to provide a weft-contacting member in a feeler of the "side-slip" type, so designed that it will not cut or injure the weft, particularly in the weaving of fine silk or rayon fabrics.

My invention further relates to arrangements and combinations of parts which will be hereinafter described and more particularly pointed out in the appended claim.

A preferred form of the invention is shown in the drawings in which

Fig. 1 is a sectional front elevation of certain parts of a weft detecting mechanism, having my improvements embodied therein;

Fig. 2 is a transverse sectional elevation, taken along the line 2—2 in Fig. 1;

Fig. 3 is an enlarged detail transverse elevation of certain parts; and

Fig. 4 is an enlarged side elevation of the same parts.

Referring to the drawings, I have shown a part of a transerrer 10, having portions 11 and 12 adapted to engage and depress a 40 bobbin or weft carrier, forcing it downward into the shuttle. The transerrer 10 has an upwardly extending arm or projection 14, to which a bell crank or lever 15 is pivoted at 16. An indicating rod 17 is pivoted at 18 to the depending portion of the bell crank 15. The rod 17 is normally held in inoperative position by a spring 19 mounted on said rod and forcing the depending arm of the bell crank to the right, as viewed in Fig. 45 1, until it engages the portion 12 of the transerrer 10. An actuating member 20 moves adjacent the outer end of the indicating rod 17, and is rendered operative when

the rod 17 is projected into the path of the member 20.

The laterally extended arm 22 of the bell crank 15 is preferably weighted to counter-balance certain parts mounted on the bell crank and about to be described. These parts comprise a bracket or stand 24 secured to the bell crank 15 by a clamping screw 25, and a U-shaped member 26 slidably mounted in the bracket or stand 24. Both legs of the member 26 are slidable in bearing openings in the foot portion 27 of the stand 24, and the longer leg of the member 26 also has a bearing in the offset top portion 28 of the stand 24. A light spring 30 is mounted on the member 26 and engages a collar 31 at its lower end, which 70 may be adjusted on the member 26 to vary the spring pressure thereon.

All of the parts thus far described are substantially similar to those shown in the Payne application above referred to, and 75 for a more complete description of the construction and operation thereof, reference is made to said prior application.

My invention does not relate specifically to the structure thus far described, but more 80 particularly to certain details of construction of the weft-engaging or contacting portion of the member 26.

This engaging or contacting portion preferably comprises a block 35, which may have 85 its upper surface grooved as indicated at 36 (Fig. 3) to receive the lower end portion of the U-shaped member 36, to which it may be secured by welding, brazing or soldering, or in any other convenient manner.

On its lower face the block 35 is provided with a flange 37 having a contacting surface which is substantially semi-circular in edge cross-section, as indicated in Fig. 4, and which is also smoothly curved longitudinally, as indicated in Fig. 3. This smoothly curved contacting surface of the member 35 has been found particularly adapted to engage the fine weft used in silk or rayon weaving, particularly when used in the type 100 of weft detecting mechanism disclosed herein, in which the weft carrier is engaged from the top and has a certain amount of forward movement during such engagement, as indicated by the full line and dotted line positions of the block 35 in Fig. 3. With the

single engaging flange continuously and smoothly curved in both directions, it is found practicable to run this form of detecting mechanism with fine silk or other filling 5 without injuring the filling or producing marks on the finished fabric.

The general operation of the detecting mechanism is described in the prior application, the block 35 being held from movement axially of the weft carrier so long as the weft carrier contains a sufficient supply 10 of weft, and slipping along the weft carrier when the weft is substantially exhausted. Such side-slipping movement rocks the bell 15 crank 15, projecting the indicating rod 17 into the path of the actuator 20, and thus initiating action by the weft replenishing mechanism.

The particular form of weft contacting 20 surface above shown and described has been found to possess very important advantages over the contacting elements previously in use and by the use of my invention the breakage or injurious marking of fine weft 25 has been substantially eliminated.

Having thus described my invention and the advantages thereof, I do not wish to be

limited to the details herein disclosed, otherwise than as set forth in the claim, but what I claim is:—

In a weft replenishing loom, a lay movable forward and rearward therein, a shuttle and weft carrier movable forward and rearward with said lay, and a side slip weft detector mounted for vertical movement toward and away from said weft carrier, said detector engaging said weft carrier on the top surface thereof while the weft carrier is moving forward relative thereto and said detector having a single weft-engaging portion disposed in a plane perpendicular to the axis of the weft carrier and elongated in the direction of said forward and rearward weft carrier movement, whereby said detector has a relative sliding movement along and between the turns of weft on said weft carrier and in the direction thereof and is thereby firmly seated in said weft turns and is held from indicating sliding movement axially of the weft carrier until said weft 50 carrier is substantially exhausted.

In testimony whereof I have hereunto affixed my signature.

THOMAS F. HAGARTY.
